UNITED STATES PATENT OFFICE.

LEE P. HYNES, OF ALBANY, NEW YORK, ASSIGNOR, BY MESNE ASSIGNMENTS, TO CONSOLIDATED CAR-HEATING COMPANY, INC., OF ALBANY, NEW YORK, A CORPORATION OF NEW YORK.

ELECTRIC HEATING SYSTEM.

Application filed December 6, 1924. Serial No. 754,333.

For a detailed description of the present form of my invention, reference may be had to the following specification and to the accompanying drawings forming a part 5 thereof.

My invention relates to heating systems particularly designed for heating railway cars, but usable under any similar conditions.

- 10 In systems of this type it is customary to employ a number of heaters in series to meet the conditions of high voltage—say 600 volts—and if an accidental ground occurs at any point along this series it brings 15 excessive voltage on those heaters of the series lying between the said ground and the trolley. These are liable to be burned out by the abnormal current which results from such excessive voltage.
- 20 It is also customary in systems of this type to keep the temperature of the car at an approximately constant degree by means of a thermostat in the car which cuts off the heaters when the car temperature exceeds a predetermined degree and reconnects them when it falls below a predetermined degree. This automatic system has heretofore involved a complicated arrangement of circuits and resistances which are 30 required for protecting the small and delicate contacts of the thermostat.

By my present invention I provide a very simple and effective means for protecting the heaters from injury in the event of a ground, and the same apparatus also provides a much simplified means of automatic regulation of the car temperature.

In the drawing H, H, etc., indicate a series of electric heaters distributed in the 40 customary way throughout an electric railway car and of any of the customary forms. These heaters receive current directly from trolley A by a circuit which includes blow-out magnet B and contacts C of a magnetically operated switch worked by a magnet D. Such switches are well known and need not be further described herein, it being noted, however, that the switch contacts C are closed by the energizing of

magnet D and opened when it becomes de- 50 energized. From contacts C the circuit goes through the four heaters H, H, etc., in series to ground at G. It will be readily understood that if an accidental ground occurs at a point on this heater circuit—say 55 at the point X—the current will then pass to ground at X, through the route of less resistance provided by the two heaters between X and the trolley rather than at G through the higher resistance route through 60 all four heaters. As a result the trolley voltage will be applied to a heater circuit which contains only the two left-hand heaters H, H and so has but half the resistance 65 of the normal heater circuit containing all four heaters. The effect will be an abnormal current in the two left-hand heaters which remain in circuit.

By my present device I provide at each heater H a small fuse K that will melt and 70 open its circuit whenever the temperature of the heater exceeds a predetermined degree. This fuse is preferably mounted on the outside of the heater case where it may be readily renewed by an authorized person 75 in the event of its fusion. These fuses K, K, etc., are included in series in a shunt circuit of high resistance which branches from the main heating circuit heretofore traced at the point a on the trolley side. Thence 80 it goes to a high artificial resistance R—of about 5000 ohms, and then through the several fuses K, K, etc., in series, to a small fuse F that will melt at approximately one ampere. Thence it goes through the switch 85 magnet D to ground at G². So long as this circuit is intact the current therein will flow in the coils of magnet D which will thus hold closed the switch contacts C that control the main heater circuit above described. 90 If, however, any one of the heaters H, H, etc., becomes overheated by reason of any accidental ground, as heretofore explained, the corresponding fuse K will open the aforesaid emergency circuit through magnet D 95 and thereby cause it to break the main heater circuit at the switch contacts C and so save the heaters from injury. But I also

provide that the same effect, viz, the de-energizing of magnet D and breaking of the main heater circuit at contacts C, shall be produced by a predetermined rise of the car 5 temperature without involving the action of any of the protection fuses K, K, etc. I do this by means of a thermostat T which controls a circuit that branches from the aforesaid emergency circuit at the point b, and, 10 if the thermostat contacts are closed, goes to ground at G³. The closure of this thermostat circuit diverts from the aforesaid switch magnet D the current which would otherwise go through it to ground at G². It 15 will be understood that the artificial resistance R, by reason of its magnitude completely dominates the current in the shunt circuit whether that circuit goes to ground through magnet D at G² or through thermostat T at G³. Thus the thermostat will 20 effectively short-circuit magnet D whenever it closes its contacts and will re-energize that magnet whenever it opens its contacts. The current, which resistance R permits to flow 25 in this emergency circuit, is so small that the circuit can be protected by the small one-ampere fuse F aforesaid. It may also be observed that the fuses K, K, etc., do not 30 act by virtue of the heating effect of the current flowing through them, but by the heat coming to them externally from an over-heated and endangered heater. So it is 35 the fuse F, that is dependent on the current it carries, which controls the shunt circuit independently of the fuses K, K, etc., although the latter are in the same circuit.

In operation current will flow from the trolley through resistance R and the fuses K, K, etc., in series, then through fuse F 40 and magnet D to ground so long as the car is colder than the thermostat setting. Coil D will be energized closing contacts C and putting current on the heaters H. For this result it is only necessary to close the main heater switch. Thereafter when the car becomes heated to the predetermined degree 45 thermostat T will make contact to ground G³ thereby short-circuiting magnet D and opening the heater switch contacts C. When the temperature falls again the heaters will 50 be automatically turned on again as above described. It will be observed that the resistance R reduces the current in the contacts of thermostat T to a minute amount which can be broken without injury or 55 danger to these contacts.

While a constant regulation of the car 60 temperature is thus secured the same apparatus will also serve to open the heater circuit in the event of an accidental ground as above described.

By means of the arrangement I have 65 described I accomplish two effects; each of which have heretofore required its own separate organization. Moreover the said ar-

rangement is much simpler than either one of the said separate organizations and more reliable.

It is to be understood that the fuses K, K, etc., are typical of any local device 70 brought into action by an abnormal degree of heat in the adjacent heaters and serving when it acts to cause the opening of the switch contacts.

What I claim as new and desire to secure 75 by Letters Patent is:

1. An electric heating system comprising an electric heater, a circuit-closing switch therefor, a magnet controlling said switch, a circuit for said magnet shunting the 80 heater with a device adjacent to the heater and responsive to excessive heat therein which controls the said magnet together with a thermostat responsive to the temperature of the apartment heated and also 85 controlling the said magnet.

2. An electric heating system comprising a plurality of heaters in series, devices exposed to the heat of the respective heaters and responsive to an excess of such heat, a 90 circuit shunting said heaters and controlled by said devices, a magnet in said circuit controlling the heater switch and a thermostat responsive to the temperature of the apartment heated controlling the said magnet. 95

3. A heater system comprising a series of heaters, a switch controlling the main heater circuit, a shunt circuit containing a high resistance and a series of devices subject to the heat of the respective heaters, and controlling the said switch, a magnet in said shunt circuit for operating the said switch and a thermostat responsive to the temperature of the apartment heated controlling the said magnet. 100

4. An electric heating system comprising a circuit containing a heater and its controlling switch, and a shunt circuit containing resistance and a device responsive to an excess of heater temperature which controls said switch, the shunt circuit having branches containing respectively a magnet controlling the heater switch and a thermostat responsive to the temperature of the apartment heated. 110

5. An electric heating system comprising a heater and a switch for the heater circuit, and a shunt circuit containing in series a resistance and a circuit-opener adjacent to and responsive to the heat of said heater and having two branches one containing a magnet controlling the heater switch and the other containing a thermostat responsive to the temperature of the apartment heated. 120

6. An electric heating system comprising a series of electric heaters and a switch therefor, a shunt circuit of high resistance containing a magnet controlling said switch, and devices in said circuit adjacent to the 125

respective heaters but external thereto acting to open the circuit in response to an excess of heat in any heater.

7. An electric heating system comprising a series of electric heaters and a magnetically operated switch therefor, thermally responsive devices adjacent to the respective heaters but external to the heater circuit acting to open the said switch upon an excess

of heat in any heater and a shunt circuit containing a resistance and controlling contacts thermostatically operated, said contacts acting to open said switch upon an excess of heat in the apartment heated.

Signed at Albany, county of Albany and State of New York, this 22nd day of November, 1924.

LEE P. HYNES.
